UNITED STATES PATENT OFFICE.

EDWARD E. O'NEILL, OF SHEFFIELD, ALABAMA, ASSIGNOR TO KING STOVE & RANGE CO., OF SHEFFIELD, ALABAMA, A CORPORATION OF ALABAMA.

DESIGN FOR A COOKING-STOVE.

41,127.

Specification for Design.

Patented Jan. 24, 1911.

Application filed October 10, 1910. Serial No. 586,422. Term of patent 14 years.

To all whom it may concern:

Be it known that I, EDWARD E. O'NEILL, a citizen of the United States, residing at Sheffield, in the county of Colbert and State of Alabama, have invented a new, original, and ornamental Design for a Cooking-Stove, of which the following is a specification, reference being had to the accompanying drawing, forming a part thereof.

The figure is a perspective view of the stove which forms this design.

The design comprises the general ornamental outlines of the stove, the general out-

lines and configuration of the legs with the scrolls appearing upon the oven door, scrolls appearing upon the fuel door, and also the scrolls appearing upon the front door or draft of the stove.

I claim—

The new, original and ornamental design for cooking stove as shown and described.

EDWARD E. O'NEILL.
